PUMP

James C. Armor, Bellevue, Pa.

Application August 20, 1934, Serial No. 740,650

10 Claims. (Cl. 103—135)

My invention relates to improvements in rotary pumps which are used for pumping non-compressible fluids and also for pumping and/or compressing compressible fluids.

5 One of the objects which I have in view is the provision in such pumps of means for simultaneously pumping two fluids.

Another object in view is the provision of 10 means for automatically reducing or relieving the load on the pump while the speed of the latter is below a predetermined value whereby to enable the pump to attain the desired operating speed more rapidly and also to automatically maintain such speed.

15 Another object in view is the better lubrication of the moving parts of the pump.

I attain the first mentioned object by employing the space between the outer casing of the pump and the interior cylinder for pumping one 20 fluid and the space within said cylinder for pumping the second fluid.

The second named object I attain by providing the space within the casing in front of the 25 rotary blade with a relief passage which is controlled by a governor-controlled valve which latter is automatically closed when the desired speed of the pump is attained.

The third named object I attain by the use of 30 my combined means for lubrication and load-control.

Further objects, and also novel features of 35 construction and of arrangement of parts, will appear from the following description:

In the accompanying drawings, wherein I have 40 illustrated practical embodiments of the principles of my invention, Fig. 1 is a longitudinal vertical section through the pump.

Fig. 2 is a cross-sectional view taken on the line 2—2 in Fig. 1.

45 Fig. 3 is an end view of the pump looking from the right in Fig. 1.

Fig. 4 is a sectional view of the revolving blade, as shown in Fig. 2, but showing a ball valve in the duct thereof.

Fig. 5 is a broken view similar to Fig. 1 but showing a modification.

Fig. 6 is a broken section taken on the line 6—6 in Fig. 5 but on a larger scale.

50 Fig. 7 is a view similar to Fig. 2 but showing a modification.

Fig. 8 is a similar view showing another modification.

Fig. 9 is a sectional view showing the character 55 of governor-valve for use in connection with the structure illustrated in Fig. 8.

Referring first to Figs. 1, 2 and 3, 1 represents a cylindrical casing supported by and having its ends closed by the heads 2 and 3. 4 represents a cylinder rotatably mounted within the casing 1 and having its ends journaled in the annular 5 shoulders 5 formed in the inner walls of the heads. Thus the heads also function as the end closures of the cylinder. The cylinder is mounted eccentrically relative to the casing, as shown, its top in approximate contact with the top interior of the casing.

6 represents a shaft extending axially of the casing 1 and having its ends journaled in the heads 2 and 3. Fixedly mounted on the shaft 6 is the radially disposed vane 7 having a segmentally enlarged counterbalancing hub 8. The vane extends through a slot 9 in the wall of the cylinder 4 into approximate contact with the inner wall of the casing 1. The walls of the slot 9 are provided with beaded or rounded edges and 20 the sides of the vane 7 are reversely curved at 10 so that the slot 9 is always sealed against the passage of fluid through the slot. The curved surfaces are carefully calculated so that at angular positions the vane completely fills the slot 25 and thus no packing is required.

The head 3 has its exterior face recessed to form a gear-pump chamber 11 which is enclosed by the removable face plate 12.

13 represents a gear mounted on the shaft 6 30 within the chamber 11 meshing with a second gear 14 mounted on a jack shaft within the chamber, the two gears forming a pump. Oil is admitted to the gear pump through a port in the face plate to which is connected the pipe 15, and 35 16 represents a passage cut in the face plate from the discharge side of the gear pump to the small axial passage 17 in the shaft 6. The inner end of the passage 17 connects with a larger axial passage 18 extending through to the other 40 end of the shaft 6 where it is cored out to form the tapered valve seat 19 arranged to be engaged by the tapered end of the slidible plug 20, which latter is provided with longitudinal grooves 21 45 extending beyond the end of the shaft.

The outer end of the plug 20 is provided with a circumferential groove 21 engaged by the fingers 22 of the bell-crank governor arms 23 pivoted intermediate of their ends to brackets 24 mounted on the shaft 6. The arms are normally retracted by the spring 25 so that when the shaft 6 is stationary or rotating at less than its predetermined operating speed, the plug 20 is held in its retracted position, shown in Fig. 1, opening the valve seat 19, but when the proper 50 55 opening the valve seat 19, but when the proper

speed is attained the plug is moved inwardly to close said valve seat.

26 represents an oil box surrounding the governor-valve and arranged to receive the oil which is expelled when the valve seat 19 is opened. The oil pipe 15 is connected to the bottom of the box 26 for the return supply of oil to the gear-pump 13—14.

27 represents a pulley on shaft 6 for rotating the same. It will be understood that any suitable application of power may be used for the shaft.

28 represents the inlet port into the space between the casing 1 and the cylinder 4, and 29 the outlet port for the same. Assuming the vane 7 to be rotating clockwise in Fig. 2, the port 28 is to the right of the top center of the casing and the port 29 to the left thereof. When the vane is rotated counterclockwise the port arrangement would be reversed. The outlet port 29 is provided with an inwardly closing check valve 30.

28' and 29' represent pipes connected respectively to the ports 28 and 29.

25 The ports 28 and 29 may be connected up in a circulating system of any kind, such for instance as a refrigerant system, or the port 29 may be connected up for the delivery of air under compression, the intake port 28 being open to atmosphere.

31 represents a radial duct in the vane 7 connected at its inner end to the passage 18 in the shaft 6 and extending to the outer end of the vane. The forward edge of the vane is cut away slightly as at 32 at the outer end of the duct 31 to insure the discharge of lubricant in front of the revolving vane.

The head 3 is provided with two passages 33 and 34 connecting with the interior of the cylinder 4. The passage 33, at the top, is provided with an outwardly opening check valve 35 while the other at the bottom is provided with an inwardly opening check valve 36. The port 33 may be connected, as by the pipe 37, to the supply end of a circulating system of any kind, while the port 34 may be connected as by the pipe 38 to the return end of the same.

In the operation of the pump, the fluid, liquid or gas, is drawn into the space between the casing 1 and the cylinder 4 through the port 28 filling the space in the rear of the traveling vane 7, while the like fluid in front of the vane is forced out of the port 29. As the vane and cylinder revolve together, but on different axes, the volume of the vane contained within the cylinder 4 varies from the minimum when the parts are as shown in Fig. 2, to the maximum when the parts have rotated into a position 180 degrees therefrom, and this variation in the effective capacity of the cylinder 4 is taken advantage of by allowing the desired fluid, such for instance as oil, to be drawn into the cylinder through the port 34 as the area expands and to be expelled through the port 33 as the area contracts.

65 Thus two different pumping or condensing actions are simultaneously performed by the pump.

A portion of the oil pumped along the shaft 6 through the passages 17 and 18 will be carried outwardly along the vane duct 31 to lubricate the wall of the casing 1 to prevent friction with the vane.

Again rising pressure in the space between the casing 1 and the cylinder 4 will be relieved out through the duct 31 and the passage 18, as long as the rotation of the shaft 6 does not attain the

predetermined operating speed and close the valve seat 19, thus relieving the load on the pump until it attains normal operating speed. As normal operating speed is approached, the governor-valve begins to close and thus, when operating speed is attained, the valve is closed. Should the pump speed be materially reduced at any time, the relief valve will automatically open, reducing the pump load and expediting the attainment of operating speed.

Referring now to Fig. 4, I have provided an outwardly closing ball valve 39 in the outer end of the duct 31 in the vane 7 with a small by-pass 40 for the outward drip of oil. This provision of ball valve and by-pass is preferable in the case of large compressors where centrifugal force might discharge too much oil through the duct 31.

Referring now to Fig. 5, I have shown the left hand bearing of the shaft 6 provided with an annular receiving chamber 40' into which the lubricant may escape through the radial port or ports 41 from the axial passage 18 when the valve head 42 on the inner end of the valve rod 43 is retracted from the valve port 19 by the spring-retraction of the governor arms 23. I also provide the end of the shaft 18 with a circumferential flange or lip 44 to prevent the outward escape of the oil along the shaft. The pipe 15, which supplies the gear pump 13—14, may be connected to the bottom of the chamber 40.

In Figs. 5 and 6, I show a transversely disposed bore 46 formed in the vane 7 intersecting the ducts 31 adjacent their outer ends, and a spring plate 47 closing such outer ends, the spring plate being held in place by plugs 48 driven or threaded into the ends of the bore. The lubricant is permitted to escape past the plate 47 through small by-pass passages 49.

In Fig. 7 the vane 7 is shown unprovided with duct or ducts 31, the casing 1 being provided with a load relief port 50 at a point adjacent the discharge port 29 but in the rear thereof in the direction of travel of the vane which is assumed to be clockwise. The port 50 is connected by a pipe 51 to the discharge passage 16 of the pump 13—14, the wall of which passage is provided with a threaded port for that purpose. The relief port or ports 50 may be in one of the heads, if preferred.

As the pump is started, or while the pump is operating at a speed less than that at which the governor valve closes, the load on the pump, such as compressed air, is relieved through the port 50, the pipe 51, the passages 16 and 18. As the speed of the pump increases, the governor valve closes, thus causing the pump to assume its full load. In such case the gear pump will force lubricant through the passage 16, pipe 51 and port 50 into the pump casing 1.

Referring now to Figs. 8 and 9, I have therein shown a solid cylinder or hub 4', provided with a plurality of blades 7' which are slidable radially in slots in the hub. In this case no axial passage is provided in the shaft and the gear pump is not employed. The air or other fluid to be pumped or compressed is admitted at 28 and discharged at 29, the interior wall of the casing 1 being provided with a circumferentially disposed groove 52 to prolong the suction action of the individual blades 7'. At the rear of the outlet port 29 in the direction of travel of the blades, which is assumed to be clockwise, the wall of the casing 1 is provided with a pressure relief port 53, while a second like port 54 is provided at about 90 degrees in the rear of the port 53. The 75

ports 53 and 54 are connected by the pipes 55 and 56, respectively, to the threaded ports which form the outer ends of the aligned passages 57 in the valve body 58 which open at their inner end 5 into the cylindrical bore 59 whose one end is open to atmosphere. 60 represents a cup-shaped valve which slides in the base of the body 58 and is arranged to close or open the inner ends of the twin passages 57 in accordance with the position 10 of the valve. The valve 60 is mounted on a stem 61, which extends through bushing 62 which is fixed in the other reduced end of the bore 59 as by the washer and nut 63. On the outer protruding end of the bushing 62 is rotatably mounted 15 the driving pulley 64. The stem 61 protrudes beyond the bushing and is provided with a grooved disk 65, which is engaged with the fingers 66 of the governor arms 67 mounted on the pulley hub and normally held in the positions shown in Fig. 20 9 by the springs 68.

When the pump is started and while its speed is less than that determined to be the proper operating speed for the pump, the valve 60 is retracted, opening the passages 57 to atmosphere, 25 and thus the load is relieved in the pump casing 1 until the desired speed of the pump is approached, when the speed of rotation of the pulley 64, which is regulated with that of the pump, causes the arms 67 to spread and thus moves the 30 valve 60 into position to close the inner ends of the passages 57, thus in effect closing the relief ports 53 and 54 and imposing the full load on the pump.

69 represents ports in the valve body 58 connected by small passages 70 with the passages 57, the passages 70 being provided with tapered adjustment screws 71 to regulate their effective capacities. The ports 69 are connected by pipes to a suitable oil supply under pressure, not shown, 40 which is at pressure greater than the internal pressure of the pump when the latter is operating under normal load.

Thus when the valve 60 closes the inner ends of the passages 57, the oil is forced outwardly of 45 said passages and through pipes 55 and 56 and ports 53 and 54 into the casing 1 to lubricate the walls thereof. The quantity of lubricant thus supplied to the pump as it operates may be properly adjusted by means of the screws 71.

50 It is evident that any desired number of relief ports may be used as desired, a like number of connections to the body 58 being provided.

While I have illustrated the principles of my invention as applied to rotary pumps, it is obvious that the same may be advantageously applied to piston pumps or to any type of pump wherein it is desirable to relieve or reduce the load until the pump attains its predetermined normal operating speed.

60 I claim:—

1. In combination with a pump for fluids, means for relieving the load on the pump, means for rendering the load-relieving means inoperative when the pump attains its predetermined speed 65 of operation, and means for supplying lubricant through the load-relieving means into the interior of the working chamber of the pump while the pump is operating at its predetermined speed.

2. In combination with a pump for fluids, 70 means for relieving the load on the pump, a valve actuated relatively to the speed of the pump and arranged to close the load-relieving means when the pump attains its predetermined operating speed, and means for supplying lubricant to 75 the pump through the load-relieving means into

the interior of the working chamber of the pump when the pump attains its predetermined operating speed.

3. In combination with a pump for fluids, an outlet passage for the relief of compressed gases 5 from the high pressure side of the working chamber of the pump for relieving the load on the pump in starting, a speed-controlled valve for said outlet passage and arranged to close when the pump attains its predetermined operating speed, and 10 a pressure oil supply communicating with said outlet passage and arranged to supply lubricant to the working chamber of the pump when said valve is closed.

4. In a rotary pump, the combination with a 15 casing, a shaft extending through said casing and a vane radially disposed on said shaft, of a passage axial of said shaft, means for supplying lubricant under pressure to one end of the passage 20 a duct in the vane and communicating at its inner end with the passage and at its other end with the interior of the casing, and a speed-controlled valve at the discharge end of the passage 25 arranged to close when the pump attains its predetermined speed of operation.

5. In a rotary pump, the combination with a 30 casing, a shaft extending through said casing and a vane radially disposed on said shaft, of a passage axial of said shaft, a duct in the vane having its inner end connected to the passage and 35 its outer end communicating with the interior of the casing, a speed-controlled valve at one end of the passage arranged to close the latter when the pump attains its predetermined operating speed, and means for supplying lubricant under 40 pressure to said passage.

6. In a rotary pump, the combination with a 45 casing, a shaft extending through said casing and a vane radially disposed on said shaft, of a passage axial of said shaft, a duct in the vane having its inner end connected to the passage and 50 its outer end communicating with the interior of the casing, a speed-controlled valve at one end of the passage arranged to close the latter when the pump attains its predetermined operating speed, and a pressure-lubricant supply connected 55 to the passage.

7. In a rotary pump, the combination with a 60 casing, a shaft extending through said casing and a vane radially disposed on said shaft, of a passage axial of said shaft, a duct in the vane having its inner end connected to the passage and 65 its outer end communicating with the interior of the casing, a speed-controlled valve at one end of the passage arranged to close the latter when the pump attains its predetermined operating speed, 70 a pressure-lubricant supply connected to the other end of said passage, and means for returning lubricant from the valve-end of the passage to the lubricant supply.

8. In a pump for fluids, the combination of an outlet passage for the escape of pressure from the high pressure side of the pump for relieving the load on the pump, a valve actuated relatively to the speed of the pump and arranged to close the 75 outlet passage when the pump attains its normal operating speed, and means for supplying lubricant to the pump through the outlet passage during the normal operation of the pump.

9. In combination with a pump for fluids, 80 means for relieving the load on the pump, means for rendering the load-relieving means inoperative when the pump attains its predetermined speed of operation, means for supplying lubricant through the load-relieving means into the 85

rior of the working chamber of the pump while the pump is operating at its predetermined speed, and means to restrict the discharge of lubricant through said load-relieving means.

5 10. In a pump for fluids, the combination of an outlet passage for the escape of pressure from the high pressure side of the chamber for relieving the load on the pump, a valve actuated relatively

to the speed of the pump and arranged to close the outlet passage when the pump attains its normal operating speed, means for supplying lubricant to the pump through said outlet passage during the normal operation of the pump, and means for restricting the flow of lubricant through said passage. 6

JAMES C. ARMOR.
